UNITED STATES PATENT OFFICE.

WILLIAM B. HAMILTON, OF TORONTO, ONTARIO, CANADA.

DESIGN FOR A PATTERN FOR SHOES.

SPECIFICATION forming part of Design No. 18,938, dated February 26, 1889.

Application filed January 22, 1889. Serial No. 287,209. Term of patent 7 years.

To all whom it may concern:

Be it known that I, WILLIAM BUCHANAN HAMILTON, a subject of the Queen of Great Britain, residing at the city of Toronto in the 5 county of York, in the Province of Ontario, Canada, have invented and produced a new and original Design for a Shoe or Slipper, of which the following is a specification, reference being had to the accompanying drawings, forming part thereof.

In the accompanying drawings like letters of reference indicate similar parts in the different figures.

Figure 1 is a perspective plan of my pattern. Fig. 2 is a perspective view of a shoe made from my pattern.

In the drawings, A represents the portion of the pattern which forms the insole; B, the portion which forms the shank; C, the vamp;

D, the quarter, and E the inside counter or 20 stiffener. The toe portions of the vamps extend from the toe of the insole on the curves α outward, and the outer edges of said vamps are slightly curved inward, as at b, and at the heel end are curved outward or scalloped, as 25 at c, and the ends of the inside counters are curved, as at d and f.

What I claim as my design is—

The design for a pattern for a shoe herein described, the same comprising the insole and 30 shank, the vamps curved at α and scalloped at c, and the inside counter having its ends curved as shown.

Toronto, January 7, 1889.

W. B. HAMILTON.

In presence of—

JOHN G. RIDOUT,

CHARLES C. BALDWIN.
